UNITED STATES PATENT OFFICE.

LOUIS G. RUGGLES, OF NEW YORK, N. Y., ASSIGNOR TO LIDGERWOOD MANUFACTURING COMPANY, OF NEW YORK, N. Y., A CORPORATION OF NEW YORK.

MULTIPLE SHEAVE-BLOCK.

1,165,363.

Specification of Letters Patent. Patented Dec. 21, 1915.

Application filed December 30, 1910. Serial No. 600,082.

To all whom it may concern:

Be it known that I, LOUIS G. RUGGLES, a citizen of the United States, and a resident of New York city, borough of Manhattan, in the county of New York and State of New York, have invented certain new and useful Improvements in Multiple Sheave-Blocks, of which the following is a specification.

My invention relates to new and useful improvements in multiple sheave blocks, and has for its purpose to provide means whereby the resultant of the forces of the loads on the different blocks and the point of suspension of said blocks, will be in substantially the same line so that the loads on the blocks will be equalized on the suspension device whereby the latter will not be subjected to lateral strains.

The invention is particularly applicable to that type of block in which the suspension means includes a swivel bolt, upon which the blocks are swiveled, the purpose being to prevent lateral strains on the bolt tending to crystallize the same, by causing the resultant of the load forces to be in line with the longitudinal axis of the bolt whereby the combined pull on the blocks is always lengthwise of the bolt.

The invention consists in the improvements to be fully described hereinafter and the novelty of which will be particularly pointed out and distinctly claimed.

I have fully and clearly illustrated my invention in the accompanying drawings to be taken as a part of this specification, and wherein—

Figure 1 is a view in side elevation of a construction embodying my invention; Fig. 2 is a view in end elevation partly in section of the same structure shown in Fig. 1; Fig. 3 is a view in end elevation showing a position taken by the parts when the pulleys are subjected to different loads.

Referring to the drawings by characters of reference, 1 designates a suspension device or connection by means of which the block is suspended from a support. The specific construction of this suspension device is immaterial but I preferably make the same in the form of a bolt 2 having at its upper end an eye 3 by means of which the pulley is connected to its support by any suitable means, not shown. At its lower end the bolt is provided with a head 4 which consists of an annulus slipped over the

lower end of the bolt and held in place by upsetting the end of said bolt, as shown at 5. Surrounding the bolt between the eye and the head 4 is a sleeve or collar 6, which is adapted to rotate freely about the bolt and is prevented from being pulled from the same by means of the head 4 above described.

Connected to the collar 6 is a compensating or equalizing means from which the blocks hereinafter to be described are suspended, said compensating means being constructed and arranged so as to equalize the load on the several pulleys or sheaves whereby the resultant of the forces represented by the products of the leverage by the load on each pulley will be on a line extending longitudinally of the suspension bolt. This compensating device may take a number of forms, but I prefer to construct the same as follows: At diametrically opposite points the sleeve 6 is provided with outwardly extending pins or trunnions 7, 7 upon each of which is suspended a plate 8, which is shown as being substantially an equilateral triangle in form, said plates being secured on the trunnions by nuts 9, 9 locked in position by cross pins 10, 10. It will be noted that in the arrangement shown these plates 8, 8 are spaced apart from each other, and I connect the same at points below the suspension bolt with connecting bolts 11, 12 which bridge the space between said plates, as shown clearly in Fig. 1, said bolts being held in place by nuts 13 on the opposite ends thereof, said nuts being held against displacement by transverse cotter pins 14. The arrangement of the trunnions 7 and bolts 11 and 12 is such that each is located at substantially one of the apexes of an equilateral triangle, the trunnion connection being at the upper apex and the bolts 11, 12 at the lower lateral apexes.

Suspended on each of the bolts 11 and 12 is a pulley, said pulleys being indicated respectively at 15 and 16, the same including the usual side plates 17 united to form a strap 18 at their upper ends by means of which they are loosely hung over the bolts 11 and 12. Between the side plates of each pulley is arranged the sheave 19 over which the load ropes pass, said pulleys being mounted on transverse axle bolts 20. At their lower ends each of the pulley blocks is provided with a downwardly extending

projection 21 which projections are connected by a link 22, which arrangement serves when there are ropes running over both of the sheaves to preserve a proper 5 rope lead by making both sheaves lie substantially parallel to each other. This result is especially advantageous when the block is used in connection with hoisting buckets or other means employing two 10 operating lines.

From the above description taken in connection with the drawings it will be seen that the triangular plates 8 constitute a differential compensating means so that, no 15 matter what load is applied to either of the two blocks, the product of the load by the leverage will balance in every case and bring the resultant of the two forces in a line extending longitudinally of the suspension device. This is due to the fact that, 20 as the two blocks swing about the point of suspension of the said differential compensating device, their respective leverages change, one increasing and the other decreasing automatically with the increase and 25 decrease of the load on the two blocks.

The specific construction of the blocks is immaterial and I do not desire to be limited to the detailed construction thereof which 30 I have shown and described.

In operation, the improved block embodying my invention may be used with a rope running over each of the sheaves of the pulleys, as shown in Fig. 3, or a rope may 35 run over but one of the sheaves. It is obvious that if a rope run over but one of the sheaves the load exerted on the sheave will pull down on the plates 8, so that the supporting bolt 11 or 12, as the case may be, 40 for that particular pulley over which the rope passes, will be below the pivotal connection 7, so that the load on the pulley will be on a line extending longitudinally through said bolt, whereby the pull on the 45 bolt will be in the direction of said line and all lateral strains on the bolt be obviated, with the result that the crystallization of the bolt or bending of the same is prevented. In the case where ropes are running over both of the sheaves, if the load 50 on both ropes is equal, the plate will swing to take the position shown in Fig. 2, so that the bolts 11 and 12 are equidistant on opposite sides of the bolt 7, the resultant 55 of the loads will be on a line extending through the longitudinal axis of the bolt 2. Should the load on the sheaves be different, then the pulley subjected to the greater load will be pulled down, so that 60 the pulleys may take a position substantially as shown in Fig. 3 with the pulley of the greater load lower than the one with the lighter load, in which case the differential compensating plates are shifted to 65 one side as shown in Fig. 3, but as in the

cases above described, the resultant of the two loads is still exerted in the direction of a line extending through the longitudinal axis of the bolt.

Having thus described my invention, what 70 I claim as new and desire to secure by Letters Patent is:—

1. In a multiple sheave block, the combination of a suspension device, a swivel on said device, a substantially equilateral 75 triangular member pivoted at one of its angles on said swivel, and blocks each suspended from said member at one of the other angles of said pivot, whereby the resultant of the 80 loads on the blocks is at all times in a line extending longitudinally through said device.

2. In a multiple sheave block, the combination of a suspension device, a pair of 85 blocks, a differential load compensating device, means for pivotally connecting said compensating device to said suspension device, and individual means for suspending 90 each of said blocks from said compensating device, said pivotal connection and the said points of suspension being located relative to each other whereby the resultant of the loads on the blocks is at all times in a line 95 extending longitudinally through said suspension device.

3. In a multiple sheave block, the combination of a suspension bolt, a swivel on the bolt, a substantially equilateral triangular member pivoted at one of its angles on 100 the swivel, and blocks, each suspended from said member at one of the other angles of said pivot, whereby the resultant of loads on the blocks is at all times in a line extending 105 longitudinally through said bolt, and means for maintaining parallelism of the blocks.

4. In a multiple sheave block, in combination, a suspension device, a member fulcrumed intermediate its ends on said suspension device, blocks each pivotally suspended 110 from said member on opposite sides of its fulcrum to swing laterally on said member, and means independent of their support for maintaining parallelism of said 115 blocks throughout movement of said member and blocks.

5. In a multiple sheave block, in combination, a suspension device, a member fulcrumed intermediate its ends on said suspension device, blocks pivotally suspended 120 respectively from said member on opposite sides of its fulcrum, and free to swing laterally on their pivots, and means separate from the suspension member for pivotally 125 connecting the blocks.

6. In a multiple sheave block, in combination, a suspension device, a member fulcrumed intermediate its ends on said suspension device, blocks pivotally suspended 130

respectively from said member on opposite sides of its fulcrum, projections on the lower ends of the blocks, and a link member pivotally connecting said projections.

- 5 7. In a multiple sheave block, a suspension bolt having a shoulder, a collar rotatably mounted on the bolt and supported by said shoulder, a differential compensating device pivoted to the said collar, and
- 10 blocks pivoted to said compensating device, the pivot between said device and said collar and the pivots for connecting the blocks to said device being disposed substantially at the angles of an equilateral triangle.
- 15 8. In a multiple sheave block, a suspension device, a differential compensating de-

vice pivotally connected to said suspension device, and blocks suspended from said compensating device, the pivot between the compensating device and the suspension device, 20 and the points of suspension between the blocks and the compensating device being disposed substantially at the angles of an equilateral triangle.

In testimony whereof I have signed my 25 name to this specification in the presence of two subscribing witnesses.
